UNITED STATES PATENT OFFICE.

GEORGE W. MCGILL, OF RIVERDALE-ON-HUDSON, NEW YORK.

SPRING-CLIP.

No. 893,353.

Specification of Letters Patent.

Patented July 14, 1908.

Application filed January 7, 1907. Serial No. 351,197.

To all whom it may concern:

Be it known that I, GEORGE W. MCGILL, a citizen of the United States, and a resident of Riverdale-on-Hudson, in the county of New York and State of New York, have invented certain new and useful Improvements in Spring-Clips, of which the following is a specification.

My invention relates to that class of spring clips that are used for temporarily binding together sheets of paper, attaching price and descriptive tickets to fabrics and other material, and for other similar uses, and it consists of a clip fashioned from a sheet metal blank of suitable size, thickness, and spring, and providing two resilient clamping members between which the papers, or other materials to be secured are held, and having means for preventing the unintentional removal of such papers, etc., therefrom.

In the accompanying drawing forming part of this specification and wherein similar letters and numerals of reference indicate corresponding parts, Figure 1 is a front elevation of the clip, Fig. 2 is a longitudinal section of Fig. 1, and Fig. 3 is an elevation similar to Fig. 1, showing the opposite or back surface of the clip. Fig. 4 is a front view in perspective of the clip showing that portion of one of its ends wherein its clamping members connect with each other, bent backward transversely. Fig. 5 is a plan view of the opposite side or surface of Fig. 4, showing such end portion folded down against the back surface of the clip. Fig. 6 is a front view in perspective of Fig. 5, and Figs. 7, 8, and 9, are views similar to Fig. 6, showing slight modifications in one of the features of the clip. Fig. 10 is a view of the clip applied in holding together sheets of paper, and showing unfolded, and projected above the clipped edges of the papers, the end portion of the clip wherein its clamping members connect with each other, and Fig. 11 is a similar view showing such end portion of the clip folded over and depending below the clipped edges of the papers and bearing against the back of the clip.

The sheet metal blank providing the clip is divided in part by a U-shaped slot 1, into two clamping members A and B, differing in size, the outer or greater member A, framing in the inner or lesser member B, with both members integrally connected together at one end and in manner to admit of the lesser

member being moved freely to and fro through the greater member nearly its entire length. The body of the member B is struck concavo-convex, or into spoon-like formation to give it rigidity, to prevent its bending, and to have it present outwardly over the surface of the papers it clamps a smooth convex surface. The upper or attached end of the member B projects slightly, as at 3, outward from the plane or front surface of the member A, providing space thereat to admit of several sheets of paper being held between the members without their clamped part being forced into or through the member A.

In the unapplied clip, as shown in the drawing, the normal set of the member B is such as to cause its free end 4, to project beyond the plane or back surface of the member A, and when the clip is applied, to bear against one surface of the clamped papers with the edge of its terminal biting into or gripping such surface. A portion of the lower inner edge of the member A (Figs. 1-6) is bent out from the plane or front surface of that member in a manner to provide a lip 5, set crosswise the axis of such member and which coacts with the adjacent terminal 4 of the member B in biting into or gripping the opposite surfaces of the clipped papers in securing them in the clip and preventing their unintentional withdrawal therefrom.

The upper end of the clip, including that portion of it to which its clamping members are rooted and from which they spring, is bent back transversely from its facing or front surface on the dotted lines 6, (Figs. 1, 3, 4) providing the flap 7, which is folded down against the back surface of the clip as shown in Figs. 5-9 and 11, and which, by doubling the metal thereat, reinforces and guards the junction of the members, disposes below such juncture that portion of the clip providing the flap which otherwise would project above such juncture and above the clipped edges of the inserted papers where, through contact with adjoining objects, it would be liable to cause the jerking of the clip from the papers. This feature is illustrated in Figs. 10 and 11, of the drawing, Fig. 10 showing the unfolded end of the clip projecting above the ends of the slot providing the members, and above the clipped edges of the inserted papers, (8) and Fig. 11, showing it folded over and depending below the top of the clip and below the edges of the

papers clipped therein. The transverse fold providing the flap 7, imparts a transverse curvature to the connecting parts or ends of the members A, B rooted therein, whereby the clamping resilience of such members is increased and the liability to fracture of the metal providing such juncture is reduced. This transverse fold 7, by reason of the clamping members A, B, being rooted there- 10 in and springing therefrom also admits of papers being entered between the members up to the line of such fold which is substantially the top of the clip. The folded over flap also provides the clip with a transverse 15 ridge 9, and with a reinforced and rigid end or head of doubled material whereby it may be conveniently seized and held during the insertion of papers and their withdrawal.

In the modification shown in Fig. 7, the 20 Lip 5 is provided by furnishing the central lower part of the member A with a curved slit and bending outward from its plane or front surface that part of the metal within the curve of such slit.

25 In the modification shown in Fig. 8, an equivalent for the lip 5 is provided by furnishing a similar part of the member A with one or more knobs 5' projecting outward from its front surface, while in Fig. 9, an equivalent for such lip is provided by furnishing the lower center of the outer edge of the free end of the member A with a lug 5" bent forward beyond the front surface of such member.

35 Having thus fully described the object, construction and operation of my invention, what I claim therein as new and desire to secure by Letters Patent is:—

1. A spring-clip of the character described 40 consisting of a piece of resilient sheet metal slotted in a manner to provide two clamping members differing in size and integrally connected in one end of the clip and having such end including the rooted end of the lesser or 45 inner member folded transversely into parallel contact with the back surface of the clip.

2. A spring-clip of the character described 50 consisting of a piece of resilient sheet metal slotted in a manner to provide two clamping members differing in size and integrally connected at one end of the clip and having such end folded transversely below the junction of the members therein with the area of such 55 junction and the top of the clip-blank seated transversely in parallel contact with a portion of the back surface of the clip.

3. A spring-clip of the character described 60 consisting of a single piece of resilient spring metal having a portion of one of its ends providing a flap which is folded back transversely upon one of its surfaces and having its body part provided with a U-shaped slot extending lengthwise throughout such body 65 part with the terminals of such slot extend-

ing into the folded over end portion or flap of the clip.

4. A spring-clip of the character described composed of a single piece of resilient sheet metal having a portion of one of its ends providing a flap which is folded back into parallel contact with one surface of the clip, the clamping members of the clip being rooted in and springing from such flap. 70

5. A spring-clip of the character described 75 consisting of a piece of resilient spring metal slotted in a manner to provide two clamping members differing in size and integrally connected at one end, the lesser or inner member being framed in by the greater or outer member and one surface of the free end of the latter member provided with rigid projecting stamped up knobs adapted to bear against and bite into the surface of articles clamped between the members. 80

6. A spring-clip of the character described consisting of a piece of resilient spring metal slotted in manner to provide two clamping members differing in size and integrally connected at one end, the lesser or inner member 90 being framed in by the greater or outer member with a portion of the lower inner edge of the slot of such greater member stamped outward from the plane of that member into a rigid lip adapted to bear thereat 95 against articles clamped between both members.

7. A spring-clip of the character described 100 consisting of a single piece of resilient sheet metal slotted in manner to provide two clamping members integrally connected near one of its ends and having such end inclusive of the roots of the clamping members folded over transversely and set in parallel contact with one of its surfaces. 105

8. In a spring clip of the character described a portion of one end of the strip of metal forming the clip folded over upon itself in manner to provide a short flap 7 of doubled over metal seated thereat in permanent parallel transverse contact with the back surface of the clip and having the body portion of the clip provided with a U shaped slot 1 extended through such fold and into said flap 7 providing the clip its clamping 110 members A and B and rooting the latter in said flap, such clamping members differing in size and the free end of the lesser member adapted to move through the free end of the greater member. 115

9. A spring-clip of the character described 120 consisting of a piece of sheet metal slotted in manner to provide two resilient clamping members differing in size and integrally connected at one end and having such end including the integral connection of both members therein folded over transversely into parallel contact with one surface of the clip, and having the free end of the outer one of 125 said members provided with a projecting 130

rigid lip adapted to bear against and bite into one surface of the articles clamped between the members.

10. A spring-clip of the character described consisting of a piece of sheet metal slotted in a manner to provide two resilient clamping members differing in size and integrally connected at one end, and having said end with its area connecting both members folded over transversely into parallel contact with one surface of the clip, the lesser member being set within the greater member and having the upper or connecting end of such lesser member projecting outward at its transverse fold from the plain or front surface of the greater member, and having the terminal of the free end of such lesser member normally projecting outward from the plane or back surface of such greater member.

11. A spring clip of the character described having a portion of one end of the metal strip from which it is fashioned folded over into parallel contact with itself and providing such end with a short transverse reinforcing flap of doubled over metal in which are rooted the clamping members of the clip, said doubled over fold of the metal providing the device a raised transverse surface forming a ridge by means of which it may be securely held while material clamped in it is being removed.

Signed at Riverdale-on-Hudson in the county of New York and State of New York this 20th day of November A. D. 1906.
